(57) **CLAIM**

The ornamental design for a handheld pipette, as shown and described.

DESCRIPTION

FIG. 1 is a right front perspective view of a handheld pipette shown with the pipette tip detached;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a perspective view of the handheld pipette of FIG. 1 shown with the pipette tip attached;

FIG. 9 is a front view thereof;

FIG. 10 is a rear view thereof;

FIG. 11 is a top view thereof;

FIG. 12 is a bottom view thereof;

FIG. 13 is a right side view thereof; and,

FIG. 14 is a left side view thereof.

The dash-dot-dash broken lines depict the boundaries of the claim and form no part thereof.

1 Claim, 14 Drawing Sheets
